DESIGN FOR A LIPSTICK CASE

Fred Frederics, New York, N. Y.

Application January 27, 1945, Serial No. 117,638

Term of patent 14 years

(Cl. D86—10)

To all whom it may concern:

Be it known that I, Fred Frederics, a citizen of the United States of America, residing in New York city, county of New York, and State of New York, have invented a new, original, and ornamental Design for a Lipstick Case, of which the following is a specification, reference being had to the accompanying drawing, forming part thereof, wherein,

The rear of the lipstick case is substantially the same in appearance as the front.

I claim:

The ornamental design for a lipstick case, substantially as shown and described.

FRED FREDERICS.
